TWIRLING BATON

John F. Hale, 3729 Greenbay Drive 45415, and
Frederick J. Miller, 2150 E. Rahn Road 45440, both
of Dayton, Ohio

Filed May 21, 1971, Ser. No. 145,984

Term of patent 14 years

Int. Cl. D21—01
U.S. Cl. D34—5

FIG-1

FIG-2

FIG-3

FIG-4

FIG-5

FIG. 1 is a perspective view of the twirling baton of our new design;

FIG. 2 is a side elevation of said new design;

FIG. 3 is an enlarged left end elevation thereof;

FIG. 4 is an enlarged right end elevation thereof; and

FIG. 5 is an enlarged side elevation of a portion of said new design.

We claim:

The ornamental design of a twirling baton, substantially as shown.
